UNITED STATES PATENT OFFICE.

EDWARD C. MEIER, OF PHOENIXVILLE, PENNSYLVANIA.

FURNACE-LINING FOR MARINE CASINGS.

1,197,842.

Specification of Letters Patent. Patented Sept. 12, 1916.

Application filed February 21, 1916. Serial No. 79,537.

To all whom it may concern:

Be it known that I, EDWARD C. MEIER, a citizen of the United States, residing at Phoenixville, in the county of Chester and State of Pennsylvania, have invented certain new and useful Improvements in Furnace-Linings for Marine Casings, of which the following is a specification.

My invention relates to improvements in furnace lining for marine casings, the object of the invention being to provide an improved construction and arrangement of fire bricks or blocks with improved means for securing the same to the casing, so that the lining cannot shake loose by reason of the motion and vibrations of the vessel.

A further object is to provide an improved construction of block which is adapted to be laid like an ordinary brick wall, and which permits the anchoring of the blocks as they are laid, so that they are effectually secured to the casing wall.

With these and other objects in view, the invention consists in certain novel features of construction and combinations and arrangements of parts as will be more fully hereinafter described and pointed out in the claims.

In the accompanying drawings: Figure 1 is a fragmentary view in horizontal section illustrating my improvements. Fig. 2 is a fragmentary view in vertical section on the line 2—2 of Fig. 1, and Fig. 3 is a face view of a fragment of the lining on a reduced scale.

1 represents a marine casing to the inner face of which my improved whole blocks 2 and half blocks 2^a are secured, and a lining 3 of any suitable material is preferably interposed between the blocks and the casing 1. Each block 2 and 2^a is of fire brick, and is provided in its upper and lower faces with recesses 4. The whole blocks 2 have two recesses in their upper and lower faces, and the half blocks have single recesses in their upper and lower faces. Each recess 4 is widest at the face of the block adjacent lining 3, and the side walls of the recess converge to the inner end of the recess where the wall of the recess is rounded as shown at 5. In the inner portion of each recess 4, a socket 6 is provided, and these sockets are sufficiently spaced from the walls of the recess 4 to permit the manipulation of a hook bolt 7 as the latter is positioned around a dowel pin 8.

The dowel pins 8 extend into the alined sockets 6, and are preferably of cast iron or wrought steel, and are of a diameter smaller than the diameter of the sockets so as to receive a slushing of fire clay 9 around the same. It will be noted, particularly by reference to Fig. 2, that the sockets 6 in the bottom of the bricks are at least twice the depth of the sockets in the tops of the bricks, or in other words, the sockets in the bottoms of the bricks are of a depth sufficient to accommodate the entire pin which is essential for repair work as will be hereinafter described. The hook bolts 7 in recesses 4 are also embedded in this fire clay 9, and the ends of the hook bolts extend through lining 3 and casing 1, and are secured by nuts 10.

As shown clearly in Fig. 3, the blocks are laid like ordinary bricks, and each block is secured against the casing by bolts, so that there is no possibility of the block working loose due to the movement of the vessel. The slushing of fire clay can be utilized to fill in all spaces, and a tight fire-proof wall can be thus formed in marine casings without danger of working loose.

It is to be understood that the apparatus may be bent or otherwise shaped to register with the openings in the marine casing, and while I have shown most of the bolts as straight, it is to be understood that they may take various positions. To illustrate this, one of the bolts is bent, and various angular dispositions may be resorted to with the bolts in order to adapt them to the casing.

While I have shown each pin as provided with a hook bolt, I may dispense with some of the hook bolts if found desirable. One important feature of my improved construction is that it permits a burnt block to be removed, and replaced by a new one.

The operation of this repair work is as follows: The brick to be renewed is chopped to pieces, and removed, and all superfluous slushing is removed from the surfaces of the bricks and from the sockets 6. Pins are then inserted in the sockets 6 in the bottom of the exposed brick in the wall, and held in place preferably by a thin metal plate. The new brick is inserted with pins 8 in its bottom sockets, and slid into place until the sockets register, when the pins will fall by gravity into locking position. I may, of course, resort to other means than a metal

plate for holding the pins against downward movement, and in some cases may merely tighten the hook bolts holding the pins, so as to give sufficient frictional engagement to prevent them from falling, and when the new block is in place, slightly release the bolt to allow the pin to fall.

While I have described my improvements in connection with a marine furnace, it is of course to be understood that I do not limit myself to this use, but wish to cover the lining in connection with any furnace with which it is adapted. I would also have it understood that the shape of the recesses may be varied, and that the purpose of the widening or flaring shape is to permit the bolts to take any angle necessary for attachment.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

30 1. A lining of the character described, comprising blocks having registering sockets of different depths, a member of greater length than the shortest socket and slidably from one socket to another, said member being designed to hold the blocks together, and a locking device adapted to hold the blocks against a casing, substantially as described.

2. A lining of the character described, comprising blocks arranged one above the other, each having registering sockets, the socket of the upper block being of greater depth than the socket of the lower block, a member of such length as to extend into the upper socket and to move partly into the lower socket, and a device connected to said member and designed to be secured to a casing, substantially as described.

3. A lining of the character described, comprising blocks having recesses therein and aligned sockets, of different depths, intersecting the recesses, pins of greater length than the short sockets and capable of fitting within the deeper sockets, said pins being

designed to project across the recesses and into the sockets of adjacent blocks, and independent devices engaging the pins and adapted to hold the blocks against a casing, substantially as described.

4. A lining of the character described, comprising blocks having recesses therein and aligned sockets, of different depths, intersecting the recesses, pins of greater length than the short sockets and capable of fitting within the deeper sockets, said pins being designed to project across the recesses and into the sockets of adjacent blocks, and independent hook bolts having portions extending around the pins, said bolts having other portions projecting through the recesses and adapted to be secured to a casing, substantially as described.

5. A lining of the character described, comprising blocks having recesses therein and aligned sockets, of different depths, intersecting the recesses, pins of greater length than the short sockets and capable of fitting within the deeper sockets, said pins being designed to project across the recesses and into the sockets of adjacent blocks, and independent hook bolts having portions extending around the pins, said bolts having other portions projecting through the recesses and adapted to be secured to a casing, substantially as described.

6. A lining of the character described, comprising blocks having registering recesses in their upper and lower faces and sockets intersecting said recesses, the sockets in the lower faces of the blocks being twice as deep as the sockets in the top faces of the blocks, pins designed to be inserted within said sockets of the lower faces and to slide partly into the sockets of the upper faces, said pins projecting across the registering recesses, and holding devices adapted to engage said pins, substantially as described.

In testimony whereof I have signed my name to this specification in the presence of two subscribing witnesses.

EDWARD C. MEIER.
